COMBINED CASKET AND VAULT DISPLAY RACK

Filed Dec. 5, 1927

Witness Louis M. Lohberg
C. J. Dykstra by Baum & Freeman Attorneys

inventor

UNITED STATES PATENT OFFICE.

LOUIS M. LOHBERG, OF DES MOINES, IOWA.

COMBINED CASKET AND VAULT DISPLAY RACK.

Application filed December 5, 1927. Serial No. 237,782.

The object of my invention is to provide a combined casket and vault display rack.

More particularly, it is my object to provide a display rack of comparatively simple and inexpensive construction, which rack 5 may be used in the display rooms of undertaking establishments, casket manufacturers and the like for conveniently displaying caskets and vaults therefor, in such relation as to effectively show both articles of merchandise.

It is my object to provide such a display rack, which may be used for supporting the base of the vault with the casket resting thereon and to hold and display the top part 15 of the vault in tilted position above the casket.

With these and other objects in view, my invention consists in the construction, arrangement and combination of the various parts of my combined casket and vault display rack, whereby the objects contemplated 20 are attained, as hereinafter more fully set forth, pointed out in my claims, and illustrated in the accompanying drawings, in which:

25 Figure 1 is a perspective view of a display rack embodying my invention and having a casket and vault installed thereon in position for display.

Figure 2 is a detail, sectional view taken 30 on the line 2—2 of Figure 1.

Figure 3 is a detail, sectional view taken 35 on the line 3—3 of Figure 2; and

Figure 4 is a perspective view of one of 40 the supports for the front part of the vault cover.

In recent years, there has been a great increase in the number of burial vaults used. Consequently there has grown up a large and increasing business in the manufacture and 45 sale of metal burial vaults.

Casket manufacturers and undertakers have found it difficult to display these vaults in a satisfactory way.

45 I have in the present invention provided a combination display rack, whereby the vault can be displayed in such manner as to facilitate the explanation of its structure, and the manner in which its base and top are connected together.

50 My rack also facilitates the display of the vault in connection with the casket in such manner that the entire display takes practi-

cally no more room on the floor than does a displayed casket.

55 My display rack comprises longitudinal frame members indicated in the accompanying drawings by the reference numeral 10. These lengthwise frame members 10 are laterally spaced a proper distance and are preferably made in the form of angle bars.

60 At each end of the rack, I provide supporting legs, hinged to the frame members 10. At each end are the two upright laterally spaced legs 12, preferably of angle iron connected 65 at their top by a transverse member 14, which may be integrally or otherwise rigidly connected with the legs 12 as may be desired.

The transverse member 14 is hinged as at 70 16 to the respective longitudinal frame members 10, so that the legs 12 may be folded from their upright position shown in Figures 1, 2 and 3 to their position illustrated in dotted lines in Figure 3.

75 For rigidly bracing the legs 12 in their upright position, a brace 18 is pivoted to each leg 12 as at 20 and is inclined upwardly and toward one of the frame members 10 and detachably but rigidly secured thereto by a removable bolt or the like 22.

80 The members 10 are also connected at their ends by transverse rigid frame members 24.

The members 14 preferably fit into the members 24 when the legs 12 are in upright position.

85 The members 24 at the front part of the rack projecting forwardly beyond the members 10, as shown at 24^a in Figures 1 and 2. Lugs or the like 26 project upwardly from the forward parts of the transverse members 24, as shown in Figure 2, and similar lugs 28 may be provided near the rear ends of the members 24.

90 The parts just described form a rigid supporting frame on which the base of a burial vault may be conveniently supported.

95 I have shown in the accompanying drawings such a base indicated at A. This base A is made of sheet metal and has at its periphery a downwardly projecting flange 30 100 terminating in a laterally projecting flange 32, so that when the base is set on a flat surface, its larger part is supported above such surface by the flanges 30 and 32.

105 The base A is placed on the frame above described, and the lugs 26 and 28 project into

the recess formed below the main part of the base A and coact with the flanges 30 for preventing the base from being accidentally slid off the display rack.

5 It will be noted that the lugs 26 and 28 are located far enough forward on the rack, so that when the vault base A is placed on the rack, it will be located a little forwardly of the fore-and-aft center of the rack, and its 10 rear flange 30 will not overhang the rear of the rack.

A casket 34 may be conveniently supported and displayed either on the rack as already 15 described or upon the base A, as shown in Figures 1 and 2.

For conveniently displaying the cover or top B of the burial vault in tilted position above the casket, I provide the following means:

20 Detachably bolted to the rear legs 12 by means of removable bolts 36 are upright angle bars 38, which project upwardly far enough to support the top or cover member B above the casket 34.

25 At its upper end, the support 38 has a portion 38^a inclined rearwardly slightly.

Welded or otherwise secured to the portion 38^a is a supporting bracket 40 having an arm 40^a adapted to project into the cover B.

30 In arranging the cover B for display, it is raised by a derrick or other means to position where its rear edge is seated against the portions 38^a of the uprights 38 and on the brackets 40.

35 For supporting the front portion of the cover B, I provide removable upright posts 42, each provided at its lower end with a U-clamp 44 in one arm of which is a set screw 46. This clamp may be secured to the flange 32 of the vault base A.

The upright support 42 is inclined rearwardly somewhat and has at its upper end a member 48, having the arms 48^a and 50 extending at right angles from each other and 45 adapted to rest underneath the lower edge of the vault top B at the corner thereof.

The respective arms 48^a and 50 have at their inner edges the hook members 52 adapted to engage around an inwardly projecting flange 54, which is found in many vault tops.

50 It will be noted that the uprights 38 are located close enough together, so that they may be used with vaults of many different lengths.

55 The uprights 42 which cooperate with the corners of the vault tops have the clamp members, whereby they can be secured to the base of the particular vault with which they are used.

60 Thus my improved display rack can be used for displaying vaults of a considerable variety of sizes, in fact all of the ordinary full sizes, together with any casket, which will rest upon the base A.

65 The legs 12 are preferably provided with

castors 56 to facilitate the movement of the rack from place to place with its load. The rack thus forms in a sense a combination display truck by means of which a vault may not only be conveniently displayed, but when mounted for display may be easily moved from place to place on the display room floor.

70 The entire display rack or truck may be folded into a relatively small space for storage or transportation.

75 For storage and shipment purposes, the uprights 38 and 42 are removed, the bolts 22 are taken out of the member 10, the legs 12 are folded up, so that there is provided a relatively small and compact package.

80 Changes may be made in the details of the construction and arrangement of the various parts of my device, and it is my intention to cover by my claims, any modified forms of structure and the use of different materials 85 or mechanical equivalents, which may be reasonably included within the scope of my claims.

I claim as my invention:

1. In a device of the class described, a supporting frame having spaced longitudinal members and spaced transverse members, provided with stop devices for holding a vault base forwardly of the longitudinal center of the frame, supporting legs at the corners of said frame, supports projecting upwardly from the rear corners of the frame for holding the rear part of a vault top, and supports adapted to be adjustably secured to a vault base resting on the frame and projecting higher than said first supports, said supports having means for engaging the under and rear surfaces of the vault top walls.

90 100 95 105 110 115 120 125 130 135 140 145 150

2. In a device of the class described, a supporting frame having spaced longitudinal members and spaced transverse members provided with stop devices for holding a vault base forwardly of the longitudinal center of the frame, supporting legs at the corners of said frame hinged to the transverse members and detachably braced to the longitudinal members, supports projecting upwardly from the rear corners of the frame for holding the rear part of a vault top, and supports adapted to be adjustably secured to a vault base resting on the frame and projecting higher than said first supports, said supports having means for engaging the under and rear surfaces of the vault top walls.

155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

3. In a device of the class described, a frame adapted to support a vault base for display thereon, an upwardly projecting member at the rear part of the frame for supporting the rear part of a vault top and upwardly extending members for supporting the front part of the vault top adapted to be detachably and adjustably mounted for permitting their adjustment forwardly or rearwardly in the device.

4. For use with a vault structure comprising

ing a base and a removable top, a device of the kind described, comprising a frame, adapted to support thereon for display, said base, and means for supporting said top comprising supporting posts at the rear of said frame, said top being supported thereon in tilted and nearly balanced position and comparatively small supporting rods extending

from the front of said frame to the front edge of said top for retaining said top in such 10 nearly balanced position with its front and rear lower edges spaced above and in substantially vertical alignment with the front and rear edges respectively of said base.

Des Moines, Iowa, November 8, 1927.

LOUIS M. LOHBERG.
